UNITED STATES PATENT OFFICE

MARCEL KOEHLER, OF LEVALLOIS-PERRET, FRANCE, ASSIGNOR TO SOCIÉTÉ ANONYME: GRAISSAGE "ALCYL," OF LEVALLOIS-PERRET, SEINE, FRANCE

APPARATUS FOR LUBRICATION BY MEANS OF CAPILLARY ELEMENTS

Application filed May 24, 1928, Serial No. 280,283, and in France June 2, 1927.

It has been specified in the United States patent application Serial No. 159,702 that the lubricating ducts were terminated by a thimble or junction piece permitting to connect them together or to couple them to the points to be lubricated, such ducts containing a capillary member having the form of a wick or cord of greater or less thickness.

In the description of the United States patent application Serial No. 159,702 the said wick was held in the thimble by means of a knot placed upon the horizontal part of a small recess which is milled in the body of the said thimble.

It was stated in the French patent of addition No. 32,823 of the 10th of January, 1927, that the said device could be replaced by a small stopping piece which is pressed upon the wick after the manner of the tag of a shoe lace, for instance.

The said stopping piece was then held by crimping in the thimble; a slight deformation of the latter maintains it in place and prevents the wick from escaping into the interior of the tube or from issuing at the exterior of the thimble.

The present improvement relates to another method of fastening by which the said wick is held in the thimble by the crimping process.

A suitable slot is milled in the said thimble and the crimping properly so called is effected by a tool of suitable shape which causes the deformation of the metal of the edges of the milled part, and thus crimps the latter upon the wick which is situated in the bottom of the slot.

The following description with reference to the appended drawings which are given by way of example sets forth the manner in which the said invention is carried into effect.

Figure 1 is a front elevational view of the coupling thimble, the right hand part of the figure being shown in section on the line X—X of Figure 3.

Figure 2 is a side elevation corresponding to Figure 1 and partly in section.

Figure 3 is a plan view partly in section on the line Y—Y of Figure 1.

Figure 4 is a corresponding view, partly in section on the line Z—Z of Figure 1.

As observed, the wick or cord 3 which serves for the lubrication is placed in a slot 1 which is formed in the interior of the thimble; when the said wick has assumed the proper position the edges of the slot 1 are driven inwardly, as shown for example at 2, by means of a suitable tool, so that the wick will be pressed and held in its recess. The projecting end is then cut off, and the wick will thus be properly secured in position.

What I claim is:—

1. A coupling device for capillary lubricating systems comprising an internally grooved thimble having an inlet orifice communicating with said groove, a flexible capillary element disposed in said orifice extending into said groove, and a pair of integral retaining lugs formed on said thimble adjacent said groove for retaining said capillary element in said groove.

2. A coupling device for capillary lubricating systems comprising an internally grooved thimble having an inlet orifice communicating with said groove, a flexible capillary element disposed in said orifice extending into said groove, and a plurality of pairs of integral retaining lugs formed on said thimble adjacent said groove for retaining said capillary element in said groove.

3. A coupling device for capillary lubricating systems comprising an internally grooved thimble having an inlet orifice communicating with said groove, a wick disposed in said orifice extending into said groove, and a pair of integral retaining lugs formed on said thimble adjacent said groove for retaining said wick in said groove.

4. A coupling device for capillary lubricating systems comprising an internally grooved thimble having an inlet orifice communicating with said groove, a wick disposed in said orifice extending into said groove, and a plurality of pairs of integral retaining lugs formed on said thimble adjacent said groove for retaining said wick in said groove.

In testimony whereof I have signed this specification.

MARCEL KOEHLER. 100
